STRAP TENSIONING DEVICE WITH
EXTENSOMETER

Edward C. Ratty, Portland, Conn., assignor to The Stanley Works, New Britain, Conn., a corporation of Connecticut

Filed Jan. 13, 1964, Ser. No. 337,493
4 Claims. (Cl. 254—51)

The present invention relates to strap tensioning devices having particular utility for tensioning nonmetallic strapping, for example conventional nylon strapping, and more particularly relates to a measuring rule useful in combination with a tensioning device for effecting control of the strap tension by providing a measure of the strap strain or elongation resulting from the strap tension.

It is a principal aim of the present invention to provide a readily useful measuring rule for a strap tensioning device for facilitating the control of the applied tension of the strap.

It is another aim of the present invention to provide an improved extensometer for a strap tensioning device which includes a measuring rule having indicia for alerting the operator when the strap has been suitably tensioned and thereby prevent the application of excessive tension.

It is a further aim of the present invention to provide an improved measuring rule of the type described having an economical construction and which may be readily attached to conventional tensioning devices.

Other objects will be in part obvious and in part pointed out more in detail hereinafter.

The invention accordingly consists in the features of construction, combination of elements and arrangement of parts which will be exemplified in the construction hereafter set forth, and the scope of the application of which will be indicated in the appended claims.

In the drawing:

FIG. 1 is a longitudinal side view, partly broken away, of an installation of a strap loop in a strap tensioning tool incorporating an accessory of the present invention;

FIG. 2 is an enlarged side view, partly broken away, of the accessory of FIG. 1 with parts removed;

FIG. 3 is an enlarged top longitudinal view, partly broken away, of the accessory of FIG. 1; and

FIG. 4 is an enlarged transverse side view of the fastener of the accessory of FIG. 1.

Referring now to the drawing in detail, the illustrated strap tensioning tool 10 is of the type disclosed in my co-pending application entitled, Feeding and Tensioning Tool for Strapping and the Like, filed September 10, 1963, and given Serial Number 308,014, now United States Patent No. 3,169,011, which issued February 9, 1965. The tool 10 is adapted for receiving the overlapping portions of a loop of strap and is operable for forwardly feeding the outer overlapping portion of strap, to the left as seen in FIG. 1, and thereby tension or tighten the loop about an enclosed article. The tool includes a cast frame having a handle 11, a base 12 with rearward and forward strap platforms 16, 18, respectively, and a forward column 20 extending outwardly from the forward platform 18. A tension wheel housing 26 is pivotally mounted on the column 20 by a pivot pin 24 and a tension or feed wheel 28 is retained within the housing by a wheel drive shaft 29. The drive shaft is operatively connected via a ratchet mechanism (not shown) to an operating lever 30 provided for rotating the tension wheel 28, clockwise as seen in FIG. 1.

The illustrated strap tensioning tool is designed primarily for use with nonmetallic strapping, such as nylon

2

strapping, which in the usual form has a width and thickness approximately the same as conventional metallic strapping. For reasons more fully described in the aforementioned copending application, the tensioning tool includes a support 34 intermediate the tension wheel 28 and the forward platform 18. Generally, however, the support 34 is loosely mounted in the column 20 immediately above the platform 18 whereby the outer overlapping portion of nonmetallic strap can be positioned between the tensioning wheel 28 and the support 34 and the inner overlapping portion of strap can be positioned between the support 34 and the platform 18, for which purpose the tension wheel housing and tension wheel can be conveniently pivoted away from the support 34 against the bias of a torsion spring 40, only partially shown. Feeding of the outer overlapping portion of strap is provided by repeated pivotal oscillation of the operating lever 30 with the inner overlapping portion of strap being restrained between the support 34 and platform 18, for which purpose the platform 18 may be provided with lateral serrations (not shown).

After the loop of strap has been appropriately tensioned, it can be suitably sealed as with a seal 46 and the free end of strap can be thereafter severed, which in the illustrated tool is accomplished at 36 by the coaction of a stationary cutting blade 47 and a pivotal cutting blade 48 manually actuated by a lever 50.

Because of the substantial mechanical advantage provided by the lever 30, and inasmuch as with the usual nonmetallic strapping the elongation or stretching of the strap resulting from tensioning is considerably more than with metallic strapping, control of the applied tension in the nonmetallic strapping is more difficult and the desired tension can be readily exceeded unintentionally and unknowingly. Moreover, the usual nonmetallic strapping when excessively tensioned tends to rupture only after some time delay. Such a delayed rupture not only results in a waste of material and labor but can also result in the not too remote possibility of damage to an article about which the ruptured strap had been applied.

In accordance with the present invention an accessory 60 for the tensioning tool is provided for indicating the tension in the loop of strap and selecting the desired tension and thereby preclude subsequent rupture of the strap. The accessory 60 functions as an extensometer and can be conveniently secured to the side of the strap tensioning tool, as illustrated, for which purpose the accessory housing 62 may be attached to the tension wheel housing 26 by a threaded fastener 64 extending through the side of the accessory housing and by an elongated threaded fastener 66. The fastener 66 additionally provides in conjunction with a similar but shorter fastener 68 for attaching a cover 70 which encloses the generally cylindrical chamber 72 of the housing.

Within the chamber 72 is a helically coillable measuring rule 74 of tempered sheet steel and preferably constructed so as to automatically withdraw or coil the rule to a stored position preferably with the outer end of the rule extending forwardly of the housing a couple inches, as shown in FIG. 1, to facilitate its being grasped by the tool operator. The inner end of the coillable rule is secured, as by a screw fastener 76, to a stationary pin 78 integrally formed centrally within the generally cylindrical opening in the housing. The pin 78 may have a flattened edge and the housing may have an opposed opening 80 for facilitating the securing of the inner end of the rule.

The housing 62 is provided with a guide slot 79 extending forwardly of and generally tangential to the

lower surface of the cylindrical opening 72 which thereby directs the rule 74 forwardly from the housing substantially parallel to the overlapping portions of the loop of strap received between the tensioning wheel and base. With the extensometer mounted on the side of the tension wheel housing the rule 74 is positioned laterally of the tension wheel and therefore laterally of the overlapping portions of strap, thereby allowing the rule to be extended parallel to but laterally spaced from the loop of strap extending forwardly of the tensioning tool and about an enclosed article.

Riveted adjacent the outer end of the coilable rule is a laterally extending clip or fastener 82 of tempered sheet steel and formed to provide a pair of resiliently engaging clip parts 84, 86. The illustrated clip is formed by reversely bending the sheet steel to provide a V-shaped intermediate clip part 84 with an apex engageable with an outer clip part 86. The clip is dimensioned to receive the strap for which purpose the clip parts are resiliently separable, with the resilient engagement with the strap being sufficient for extending the rule and yet allow for manually sliding the clip on the strap for adjustment of the extension of the rule.

The coilable rule is used by clipping the rule to a loop of strap forwardly of the tensioning tool, preferably after all the slack in the loop has been taken up and before the loop has been placed under more than minimal tension. The clip is then attached to the loop with a predetermined length of strap between the clip and tool, and where necessary with the rule wrapped partly about the article enclosed by the loop of strap. For this purpose, appropriate indicia may be placed on the surface of the rule, which when in registration with a rule index 90, provided by the edge between the forward substantially flat face of the rule housing 62 and the guide slot 79, indicates the extension of the rule and therefore the length of strap between the clip and the tensioning tool. With subsequent tensioning of the strap loop, the nonmetallic strap will undergo some lengthening or strain, with the strain being a function of the tension on the strap. Accordingly, indicia can be provided on the rule indicating the lengthening of the predetermined length of strap and therefore the tension of the strap. Preferably, the indicia take the form of colored rule sections 91 which can thereby be readily viewed by the tool operator, and with each color having a leading edge providing an indication of the selected length of strap and the trailing edge providing a measure of the tension of the strap. By using several colored sections different strap tensions can be indicated and/or the rule can be useful with straps having different stress/strain relationships.

Thus it can be seen that the extensometer facilitates the controlling of the strap tension by the convenient step of merely attaching the rule clip to the loop after the loop slack has been taken up and by sliding the clip along the loop until the appropriate indicia on the rule is in registration with the rule index 90. During the tensioning of the loop of strap by the handle 30, as soon as the appropriate indicia on the rule is viewed in registry with the index, the appropriate tension is obtained. The extensometer is useful with the banding of irregular shaped articles and with articles of large and small sizes without special calibration, and where the tensioning tool is to be used with various strapping materials, the rule can be appropriately calibrated in advance by coloring appropriate sections of the rule and thereby avoid subsequent technical or mathematical considerations by the operator of the tensioning device.

As will be apparent to persons skilled in the art, various modifications and adaptations of the structure above described will become readily apparent without departure from the spirit and scope of the invention, the scope of which is defined in the appended claims.

I claim:

1. In combination with a tensioning tool operable for tensioning a loop of nonmetallic strap with overlapping outer and inner strap portions and having a base and a tension wheel pivotally mounted outward of the base for receiving the overlapping strap portions therebetween, the tension wheel being pivotal into operative engagement with the outer strap portion for forward feeding of the outer strap portion with the inner strap portion being restrained, an extensometer comprising a coilable metal rule having an inner end secured to the tensioning tool laterally of the tensioning wheel and an outer end extendable forwardly adjacent the loop of strap and laterally spaced therefrom, a laterally extending clip fixed to adjacent the outer end of the rule having a pair of resiliently separable clip portions adapted for resiliently retaining the strap therebetween, a rule index mounted on the tool, and indicia means on the rule cooperative with the index for positioning the clip on the strap a predetermined distance from the tool and for ascertaining the strap strain resulting from the subsequent operation of the tool.

2. In combination with a tensioning tool operable for tensioning a loop of nonmetallic strap with overlapping outer and inner strap portions and having a base adapted for receiving the inner strap portion, a loosely mounted support outward of the base adapted for receiving the outer strap portion, a tension wheel housing pivotally mounted outward of the support, a tension wheel rotatably mounted in the housing and pivotal with the housing into engagement with the outer strap portion for forwardly feeding the outer strap portion and with the support being urged inwardly for clamping the inner strap portion against the base, an extensometer comprising a coilable rule housing, fastener means fixing the rule housing to the tension wheel housing laterally of the tension wheel, the rule housing having a forward slot opening, a pin mounted centrally within the housing with its axis parallel to the axis of the tension wheel, a metal rule coillable within the housing with its inner end secured to the central pin and extending through said forward slot, clip means fixed adjacent the outer end of the rule for affixing the rule to the strap loop, and indicia means on the rule for affixing the clip on the strap loop a predetermined distance forwardly of the tensioning tool and for indicating the strap strain resulting from the subsequent operation of the tool.

3. In combination with a tensioning tool operable for tensioning a loop of strap with overlapping outer and inner strap portions and having a base and a tension wheel mounted outward of the base for receiving the overlapping strap portions therebetween, the tension wheel being adapted for operative engagement with the outer strap portion for forward feeding of the outer strap portion with the inner strap portion being restrained, and extensometer comprising an elongated measuring rule, means for mounting the measuring rule on the tensioning tool for movement forwardly of the tool parallel to and adjacent the loop of strap, clip means on the forward end of the elongated rule for attaching the forward end of the rule to the loop of strap, a rule index mounted on the tool, and indicia means on the rule cooperative with the index for positioning the clip means on the strap a predetermined distance from the tool and for providing a stress limit indicator for the following tensioning operation by the tensioning tool.

4. In combination with a tensioning tool operable for tensioning a loop of strap with overlapping outer and inner strap portions and having a base and a tension wheel mounted outward of the base for receiving the overlapping strap portions therebetween, the tension wheel being adapted for operative engagement with the outer strap portion for forward feeding of the outer strap portion

with the inner strap portion being restrained, an extensometer comprising a coilable rule, means mounting the coilable rule on the tensioning tool for extension forwardly of the tool parallel to and adjacent the loop of strap, clip means on the forward end of the coilable rule for attaching the forward end of the rule to the loop of strap, a rule index mounted on the tool, and indicia means including colored sections along the rule cooperative with the rule index for positioning the clip means on the strap a predetermined distance from the tool and for providing stress limit indicators for the operation of the tool.
